UNITED STATES PATENT OFFICE.

WILLIAM F. SLAGLE, OF PUTNEYVILLE, PENNSYLVANIA.

HORSESHOE.

Application filed November 1, 1926. Serial No. 145,616.

This invention relates to certain new and useful improvements in horseshoes, and has more particular reference to improved means for detachably securing toe and heel calks of 5 horseshoes in place so that replacement of worn out calks can be readily effected, and whereby the calks are effectively and rigidly fixed in place for use.

A further object is to provide an improved horse shoe having detachable toe and heel calks secured in place so as to present an extremely simple and durable construction.

Other objects will appear as the nature of 15 the invention is better understood, and the same consists in the novel form, combination, and arrangement of parts hereinafter more fully described, shown in the accompanying drawings, and claimed.

20 In the drawings, wherein like reference characters indicate corresponding parts throughout the several views:-

Fig. 1 is a bottom plan view of a horseshoe constructed in accordance with the present invention;

Fig. 2 is a rear edge elevational view of the device shown in Fig. 1;

Fig. 3 is a fragmentary perspective view showing a heel end of the horseshoe illustrated in Fig. 1 with the associated heel calk removed;

Fig. 4 is a perspective view of one of the heel calks employed in the shoe shown in Figs. 1 and 2;

Fig. 5 is a side edge elevational view of the device shown in Fig. 1;

Fig. 6 is a central longitudinal section taken substantially upon line 6—6 of Fig. 1;

Fig. 7 is a transverse section taken substantially upon line 7—7 of Fig. 6;

Fig. 8 is a fragmentary section taken substantially upon line 8—8 of Fig. 1;

Fig. 9 is a transverse section taken upon line 9—9 of Fig. 1; and

Fig. 10 is a perspective view of the toe calk of the shoe shown in Fig. 1.

Referring more in detail to the drawings, the body 5 of the shoe is of the usual shape and has the ordinary arrangement of 50 countersunk nail holes 6 for facilitating attachment of the shoe to the horse's hoof. The heel ends of the shoe are constructed alike for receiving the respective heel calks 7, and each heel end is formed with depending parallel flanges 8 which form the side

walls of a longitudinal socket for receiving the shank 9 of the heel calk 7. The rear ends of the flanges 8 are connected by a transverse flange 10 which closes the rear end of the socket and forms an abutment for 60 the rear end of the calk shank 9, whereby rearward displacement of the calk from the socket is positively prevented. The rear end of the shank 9 terminates forwardly of the rear side of the calk 7, as indicated at 11, so 65 that the base of the calk flatly engages the lower edge of the flange 10 for being effectively braced when in use. The inner side walls of the flanges 8 are undercut or beveled as at 12, and the sides of the shank 9 are 70 beveled to substantially correspond therewith so that the shank will snugly fit in the socket and be frictionally retained therein after being driven into place by the use of a hammer or the like. The inclination of 75 the bevel of the sides of the shank 9 gradually increases in a rearward direction so that the shank is somewhat tapered smaller toward its rear end for facilitating insertion of the rear end of the shank in the forward 80 end of the socket preparatory to driving the calk in place. The transverse wedge-shaped ground-engaging member of the heel calk is wider than and projects beyond opposite sides of the rear end of the shank 9 so as to 85 rest flatly at its base against the lower edges of the rear end portions of the flanges 8, and it will thus be seen that the calks are solidly connected to the heel ends of the shoe so that impacts thereon are transmitted uniformly to the heel ends of the shoe. With 90 the above construction, it is simply necessary to lock the heel calks against forward displacement from the sockets, and this is preferably accomplished by cross-pinning the 95 calks as at 13, a cross-pin being inserted in registering transverse openings in the forward ends of each pair of flanges 8 and the shank 9 of the cooperating calk, and the ends of the pin being headed as at 14 by a riveting 100 operation so as to be retained in place. This avoids the use of objectionable screws, and the flanges 8 relieve the cross-pins of considerable strain in holding the calks in place.

The toe portion of the shoe is constructed 105 for receiving the toe calk 15, and such toe portion of the shoe is formed with depending parallel transverse flanges 8^a which form the side walls of a transverse socket for receiving the shank 9^a of the toe calk 15. 110

The ends of the flanges 8^a are connected at one end of the socket formed thereby, by a flange 10^a which closes said end of the socket and forms an abutment for the adjacent end of the calk shank 9^a, whereby sidewise displacement of the calk 15 from the socket is positively prevented in one direction. In this instance, the calk body 15 extends parallel with the shank 9^a instead of transversely thereto as is the case with respect to 5 the heel calk, and the base of the calk body 15 projects forwardly of the front side of the shank 9^a so as to flatly engage the lower edge of the front one of the flanges 8^a for being effectively braced when in use. The 10 inner walls of the flanges 8^a are beveled or undercut for snug reception of the beveled shank 9^a, substantially as described above with respect to the shank 9 and flanges 8. However, the sides of the shank 9^a are 15 beveled at a uniform inclination from end to end instead of at a gradually increasing inclination as is the case with the beveling of the sides of the heel calk shanks 9. The toe calk is locked in place against sidewise displacement in the other direction out of the 20 socket by cross-pinning as indicated at 13^a, substantially in the same manner in which the heel calks are cross-pinned in place at 13 and as described above. It will be noted 25 that in all instances the cross-pin is provided near the open end of the calk shank receiving socket.

In order to remove a calk it will simply 30 be necessary to cut a head off of one end of the cross-pin holding the same in place, whereupon the calk may be driven out of the socket by the use of a hammer in an expeditious manner. As indicated at 11^a 35 the shank 9^a terminates short of one end of the calk body 15 so that an end of the latter projects for flatly contacting with the lower edge of the flange 10^a at its base. This has a bracing action and at the same time permits the toe calk to project equal distances 40 to opposite sides of the longitudinal center of the horseshoe body even though the flange 10^a is employed.

From the foregoing description it is believed 45 that the construction and operation as well as the advantages of the present invention will be readily understood and appreciated by those skilled in the art.

Minor changes may be made without departing 50 from the spirit and scope of the invention as claimed.

What I claim as new is:—

In a horseshoe, a body provided upon its under side at one end with spaced flanges flush at their outer sides with the portion of 60 the body upon which they are formed, and a flange extending transversely between the rear ends of the first-mentioned flanges and having its outer side flush with the rear end of the portion of the body upon which the 65 flanges are formed, the under sides of the flanges occupying a common plane parallel to the under side of the body, the opposing sides of the first-mentioned flanges occupying planes diverging upwardly in the direction of the under side of the body, the inner side of the second-mentioned flange occupying a plane perpendicular to the under side of the body, and a calk comprising a body 70 having downwardly converging inclined 75 front and rear sides and a flat upper side, and a shank integral with the calk body at the upper side of the body, the shank having a straight rear end perpendicular to the plane of the upper side of the body of the calk and spaced 80 inwardly from the forward side of said body to provide a shoulder portion, the said shank of the calk having its opposite sides beveled and occupying upwardly diverging planes, 85 the said shank being fitted between the first-mentioned flanges upon the body of the horseshoe with the rear end of the shank abutting against the inner face of the second-mentioned flange and with the upper side of the 90 calk body resting in contact with the under sides of the first and second mentioned flanges, the said shank of the calk projecting beyond the forward side of the calk body and having a beveled end inclined upwardly and rearwardly with respect to the under side of the body of the horseshoe and terminating at its lower portion flush with the forward ends of the first-mentioned flanges upon the horseshoe body, the under 95 side of the shank of the calk being inclined upwardly and forwardly from the forward face of the calk body to the said beveled end of the shank, the said shank and the first-mentioned flanges near their forward ends 100 being provided with registering openings, and a securing element secured through said openings.

In testimony whereof I affix my signature.

WILLIAM F. SLAGLE.
